UNITED STATES PATENT OFFICE

2,537,877

BIS-(2-AZOLYL) CARBANILIDES

Burt H. Carroll and Robert H. Sprague, Rochester, N. Y., assignors to Eastman Kodak Company, Rochester, N. Y., a corporation of New Jersey

No Drawing. Application January 19, 1950,
Serial No. 139,542

11 Claims. (Cl. 260—304)

1

This invention relates to new organic compounds useful as absorbents of ultra-violet light and more particularly to bis-(2-azolyl) carbamides and to a process for their preparation.

It is known that color photographs on multi-layer photographic material, particularly where the dye images are formed in sensitive emulsion layers by color development, are susceptible to fading and discoloration by the action of ultra-violet light to which the photographs are subjected during viewing. It is also known that the residual couplers contained in the emulsion layers after formation of the picture images in certain processes, are attacked by ultra-violet light and form a stain which is undesirable in the finished photograph. The action of ultra-violet light on finished color photographs is particularly noticeable in positive prints on paper or other opaque supports since this type of print is frequently viewed in daylight where there is a high content of ultra-violet radiation.

It is also known that color photographs, especially where the dye images are formed by color development, can be protected from the fading and discoloration caused by ultra-violet light by applying to the finished color photograph a layer of gelatin or other colloidal material having therein an ultra-violet absorbing material. A process of this type in which aesculin, quinine,

2

midity and substantially no absorption in the visible region of the spectrum. The absorbents naturally must have solubility in water or organic solvents used for incorporating them in the particular colloid layer. One of the commonest defects of compounds absorbing in the ultra-violet region is that the compound is colored, usually yellow, or develops such coloration upon exposure to ultra-violet light. Other compounds have objectionable fluorescence under ultra-violet light. The result is to alter the color of the colored object seen through the overlying filter layer or packaging material.

Various thiazoles, benzothiazoles and imidazoles are known which absorb in the ultra-violet region, but previous to our discovery none were known which possessed all of the desired properties set forth above. For example, 2-(p-aminophenyl) 6-methyl-benzothiazole absorbs in the desired region of the spectrum, and while organic colloid layers containing the compound are initially substantially colorless, exposure of the layers to ultra-violet light causes yellowing of the layer.

We have discovered a class of compounds having the desired properties of ultra-violet absorbents. The compounds are the bases or the quaternized salts of bis-(2-azolyl) carbamides represented by the general formulas:

primuline, disalicylbenzidine, etc., are used as ultra-violet absorbing materials in a gelatin over-coating layer is described in British Patent 565,929. Salminen et al., U. S. application Serial No. 91,422, filed May 4, 1949, discloses another process for applying ultra-violet absorbents to photographic prints.

It is also known to incorporate ultra-violet absorbents in sheeting such as thin films of gelatin, cellulose esters, resins, etc., in order to provide photographic filters, or transparent wrapping materials for the protection of foodstuffs dyed textile and similar materials from the effects of ultra-violet light.

In the mentioned and other uses the ultra-violet absorbents must possess, among other properties, good stability to light, heat and hu-

40 where Z represents the non-metallic atoms necessary to complete a heterocyclic nucleus selected from the group consisting of the benzothiazol, thiazol and imidazol series, D represents the non-metallic atoms necessary to complete a mono-nuclear aryl radical, n represents a positive integer of from 1 to 10, and n' represents a positive integer of from 1 to 2, R represents an alkyl group and X represents an acid radical.

Accordingly, it is one of the objects of our invention to provide a new class of compounds and 50 a process for preparing them. Another object is to provide colloid layers containing the compounds suitable for use for filtering out ultra-violet radiations. A further object is to provide elements protected against ultra-violet light by means of colloid layers containing the absorb-

3

ents. Other objects will become apparent from considerations of the following description of our invention.

According to the process of preparing our compounds we react a di-acid chloride, e. g., phosgene, oxalyl, malonyl, succinyl, glutaryl or adipyl chlorides, etc. with a 2-(p-aminophenyl)azole such as a 2-(p-aminophenyl)-benzothiazole, -thiazole or -imidazole etc., to form the corresponding bis-compound of formula above. Suit- 10 able azoles are:

Benzothiazoles

2-p-aminophenyl-6-methyl-7-sulfonylbenzothiazole
2-p-amino-m-sulfophenyl-6-methyl-7-sulfonylbenzothiazole
2-p-aminophenylbenzothiazole
2-p-aminophenyl-6-methyl-benzothiazole

The benzothiazoles can have other substituents on the nuclei in addition to or in place of those indicated such as halogen, ethyl, propyl, etc.

Thiazoles

2-p-aminophenylthiazole
2-p-aminophenyl-4-phenylthiazole
2-p-aminophenyl-4-sulfophenylthiazole
2-p-amino-m-sulfophenylthiazole
2-p-aminophenyl-4-methylthiazole

Imidazoles

2-p-aminophenylimidazole
2-p-aminophenyl-4-phenylimidazole
2-p-aminophenyl-4-methylimidazole
2-p-amino-m-sulfophenylimidazole
2-p-aminophenyl-5-methylimidazole

4

be reacted directly by heating with our new bases to give useful quaternary salts include dimethylsulfate, diethylsulfate, methyl benzenesulfonate, ethyl benzenesulfonate, n-propyl benzenesulfonate, methyl p-toluenesulfonate, ethyl p-toluenesulfonate, n-propyl p-toluenesulfonate, n-butyl p-toluenesulfonate, isobutyl p-toluenesulfonate, sec-n-butyl p-toluenesulfonate, n-amyl p-toluenesulfonate, etc. Compounds wherein X in the above formula represents a bromide ion or an iodide ion can conveniently be prepared by interacting a quaternary salt of our bis-compounds, such as the dimetho-p-toluenesulfonate, with a solution of potassium bromide and potassium iodide, respectively. Compounds where X represents a perchlorate (ClO_4^-) ion can advantageously be prepared by interacting a quaternary salt of our bis-compounds, such as the dimetho-p-toluenesulfonate, with a solution of sodium perchlorate. Compounds where X represents a chloride ion can conveniently be obtained by interacting a quaternary salt where X represents an iodide ion with a methanol suspension of silver chloride. Other methods of preparing our new quaternary ammonium compounds can be used, if desired. Such methods are commonly employed and are well known to those skilled in the art. For example, compounds where X represents a halide ion can be prepared by heating our new free bases with the appropriate alkyl halide in a sealed tube.

The following examples will serve to further illustrate the manner in which we practice our invention.

Example I.—4,4' - bis - (6 - methyl - 7 - sulfo-2-benzothiazolyl) carbanilide disodium salt

The thiazoles and imidazoles may have other substituents in addition to or in place of those indicated, e. g., halogen, in the 4 and 5 positions and the o- and m-positions of the phenyl group.

The quaternary ammonium salts of our invention are obtained by treatment of the benzothiazole, thiazole and imidazol free bases of the bis-compounds, for example, with an alkyl ester of p-toluenesulfonic acid. A method for preparing quaternary ammonium compounds of our new bases comprises treating one of the alkyl sulfonic or sulfonic acid ester addition salts of our new bases with an inorganic salt in a solvent (water or alcohol) (i. e., by double decomposition). The quaternary addition compounds made from the bis-azole bases have the structure

50 One hundred grams of 2-p-aminophenyl-6-methyl-7-sulfonylbenzothiazole sodium salt are dissolved in 4 liters of hot water, 50 grams of sodium carbonate monohydrate are added and a current of phosgene gas is passed into the solution with stirring and heating on the steam bath. During the reaction, further quantities of sodium carbonate are added as required to keep the solution alkaline (140 g. in all). Phosgene is passed into the solution until a sample of the solution when diazotized and added to epsilon acid in alkaline solution gives only a trace of color. Five hundred grams of sodium chloride are added to the hot solution, stirring is continued for one hour while chilling to 20° C. The product is collected on a suction filter and dried in a vacuum

70 wherein R is an alkyl group such as methyl, ethyl, n-propyl, isopropyl, n-butyl, isobutyl, sec-n-butyl, amyl, etc., and X is an anion (or acid radical), such as halide (e. g., Cl^- , Br^- , I^-), perchlorate (ClO_4^-), thiocyanato (SCN^-), alkylsulfate (e. g., CH_3SO_4^-), benzenesulfonate ($\text{C}_6\text{H}_5\text{SO}_3^-$), p-toluenesulfonate (p- $\text{CH}_3\text{C}_6\text{H}_4\text{SO}_3^-$), etc. Typical esters which can

75 over calcium chloride. The yield of nearly colorless material is 95 g., 91%. The product is purified by recrystallization from methyl alcohol (80 cc. per gram). The yield of purified material is 71.6 g., 69%. A solution of one part in 150,000 in water in a 1 cm. layer gives a maximum density of .74 at 347 m μ . The free acid form is obtained by neutralizing with mineral acid.

Example II.—4,4'-bis-(6-methyl-7-sulfo-2-benzothiazolyl) adipanilide disodium salt

A mixture of 17.5 g. of 2-aminophenyl-6-methyl-7-sulfo-2-benzothiazole sodium salt and 300 cc. of chlorobenzene is heated to the boiling point and 10 cc. of triethylamine are added. An excess (8 g.) of adipylchloride is added in small portions with stirring. A vigorous reaction takes place and sticky orange solid separates out of the mixture at once. The mixture is boiled and stirred for one hour, chilled and the solvent decanted. The residue is stirred with two 50 cc. portions of acetone and finally dissolved in 400 cc. of warm water and filtered. The product is salted out with 50 g. of sodium chloride, collected on a suction filter and dried on the steam bath. The yield of yellow crystals is 9.0 g. The product is purified by solution in water and salting out with sodium chloride. The yield of purified material is 2.8 g. A solution of one part in 50,000 in water in a 1 cm. layer gives a maximum density

of 1.27 at 324 m μ . The free acid is obtained by neutralizing with mineral acid.

Example III.—4,4'-bis-(6-methyl-7-sulfo-2-benzothiazolyl)-2,2'-disulfocarbanilide tetra sodium salt

A mixture of 44.4 g. (2 mols.) of 2-(p-aminophenyl)-6-methyl-7-sulfo-2-benzothiazole disodium salt (prepared by the method disclosed in FIAT Report 1016, p. 17), 25 g. of sodium bicarbonate and 9 l. of water was heated on the steam bath with stirring. A current of phosgene gas was passed into the hot solution with stirring for 8 hours, additional 25-g. quantities of sodium bicarbonate being added at 2-hour intervals. The next day phosgene was again passed in for 8 hours and 250 g. of sodium bicarbonate added in five portions. After standing at room temperature overnight the mixture was filtered with suction and the damp filter cake was dissolved in 4 l. of hot water. The solution was stirred and heated on the steam bath with 15 g. of Norite decolorizing carbon, filtered and the product salted out with 250 g. of sodium chloride. The product was recrystallized from 3500 cc. of methyl alcohol. The yield of colorless crystals was 12.4 g.

Example IV.—4,4'-bis-(3,6-dimethyl-2-benzothiazolium)-carbanilide di-p-toluenesulfonate

Five grams (1 mol.) of 4,4'-bis-(6-methyl-2-benzothiazolyl)-carbanilide, 7.6 g. (2 mols. plus

excess) of methyl p-tolene-sulfonate and 50 cc. of nitrobenzene were refluxed together for 30 minutes, cooled, and the clear solution poured slowly into 500 cc. of acetone. The mixture was allowed to crystallize overnight and the product collected on a filter, washed on the filter with acetone and recrystallized from 1500 cc. 95% ethyl alcohol. The yield of pale yellow crystals was 5.0 g.

The corresponding dietho-ethyl sulfate was prepared similarly using 6.2 g. of diethyl sulfate in place of the methyl p-toluenesulfonate. The mixture was refluxed for 10 minutes, cooled, stirred with several 200-cc. portions of ether until crystalline and filtered off. After recrystallization from 100 cc. of alcohol the yield of yellow powder was 7.0 g.

Example V.—4,4'-bis-(6-methyl-2-benzothiazolyl)-carbanilide

A mixture of 24.0 g. (2 mols.) of 2-p-aminophenyl-6-methyl benzothiazole and 400 cc. of o-dichlorobenzene was stirred and heated on the steam bath until solution was complete. Phosgene gas was then passed into the solution with stirring and heating for one hour until a sample

gave a negative diazo test. The solution was chilled to 25°, the solid product collected on a suction filter, washed on the filter with 50 cc. of o-dichlorobenzene, and dried. The yield of yellow crystals was 26.5 g. Soluble impurities were removed by extraction with 300 cc. of hot pyridine. The yield of colorless purified material was 19.0 g.

Other bis-compounds of our invention can be obtained in the manner of the above examples by treatment of the selected p-aminophenyl-2-azole with one of the mentioned diacid chlorides. As previously mentioned, the compounds of the invention are useful in colloid filter layers of all kinds. When used for protecting photographic color prints, it is preferred to treat the prints the manner described in the Salminen et al. invention. Alternately, the color print can be coated with a colloid layer containing the absorber, e. g., a dispersion of the sodium salt of the absorber, or a quaternized derivative, in aqueous gelatin solution can be coated onto the print.

Chemical structure 6: 4,4'-bis-(6-methyl-2-benzothiazolyl)-carbanilide di-p-toluenesulfonate. It is similar to structure 5, but the sulfonate group (SO3Na-) is replaced by a dimethylsulfonate group (SO3-O-C6H4-CH3).

We also include as a part of our invention incorporating the novel absorbers into a pre-sensitized color-film or paper. In this case the absorber is preferably applied as a separate colloid layer to the emulsion coated product and those absorbers, e. g. that of Example V, which are relatively insoluble in processing solutions are pre-

5 the non-metallic atoms necessary to complete a mononuclear aryl radical, n represents a positive integer of from 1 to 10 and n' represents a positive integer from 1 to 2, R represents an alkyl group and X represents an acid radical.

2. A compound selected from those represented by the general formulas:

and

ferred for this purpose. The quaternary ammonium derivatives are especially useful in those cases where organic solvents especially alcohols, acetone, etc., are used for applying a colloid layer (e. g. cellulose ester) containing the absorber to the object to be protected from ultraviolet light. Similarly, the quaternized compounds are preferred for use in making transparent sheeting such as cellulose acetate, since it is most

20 25 wherein X represents the non-metallic atoms necessary to complete a heterocyclic nucleus selected from the group consisting of the benzothiazol, thiazol and imidazol series, D represents the non-metallic atoms necessary to complete a mononuclear aryl radical, R represents an alkyl group and X represents an acid radical.

3. A compound selected from those represented by the general formulas:

and

convenient to incorporate the absorber into the organic solvent dope of the cellulose ester before 40 coating the sheet, although the absorber can be applied in a separate colloid layer to the sheeting.

It will be understood that the examples and modifications included herein are illustrative only and that our invention is to be taken as limited only by the scope of the appended claims.

We claim:

40 wherein Z represents the non-metallic atoms necessary to complete a heterocyclic nucleus selected from the group consisting of the benzothiazol, thiazol and imidazol series, D represents the non-metallic atoms necessary to complete a mononuclear aryl radical, n represents a positive integer from 1 to 10, R represents an alkyl group, and X represents an acid radical.

45 4. A compound selected from those represented by the general formulas:

and

1. A compound selected from those represented by the general formulas:

wherein X represents the non-metallic atoms necessary to complete a heterocyclic nucleus of

and

wherein Z represents the non-metallic atoms necessary to complete a heterocyclic nucleus selected from the group consisting of the benzothiazol, thiazol and imidazol series, D represents

the benzothiazol series, D represents the non-metallic atoms necessary to complete an aryl group of the benzene series, R represents an alkyl group and X represents an acid radical.

5. A compound selected from those represented by the general formulas:

and

wherein Z represents the non-metallic atoms necessary to complete a heterocyclic nucleus of the thiazol series, D represents the non-metallic atoms necessary to complete an aryl group of the benzene series, R represents an alkyl group and X represents an acid radical.

6. A compound selected from those represented by the general formulas:

and

wherein Z represents the non-metallic atoms necessary to complete a heterocyclic nucleus of the imidazol series, D represents the non-metallic atoms necessary to complete an aryl group of the benzene series, R represents an alkyl group and 35 X represents an acid radical.

7. The compound: 4,4'-bis-(6-methyl-7-sulfo-2-benzothiazolyl) carbanilide disodium salt.

15

8. The compound: 4,4'-bis-(6-methyl-7-sulfo-2-benzothiazolyl)-2,2'-disulfo carbanilide tetra sodium salt.

9. The compound: 4,4'-bis-(6-methyl-7-sulfo-2-benzothiazolyl) adipanilide disodium salt.

10. The compound: 4,4'-bis-(3,6-dimethyl-2-benzothiazolium)-carbanilide di-p-toluenesulfonate.

11. The compound: 4,4'-bis-(6-methyl-2-benzothiazolyl)-carbanilide.

Certificate of Correction

Patent No. 2,537,877

January 9, 1951

BURT H. CARROLL ET AL.

It is hereby certified that error appears in the printed specification of the above numbered patent requiring correction as follows:

Column 5, line 9, for "2-aminophenyl" read *2-p-aminophenyl*; column 6, line 63, strike out the words "with aqueous solutions of one of the absorbers in" and insert the same before "the manner" in line 62, same column; columns 7 and 8, claim 1, for that portion of the first formula reading

and that the said Letters Patent should be read as corrected above, so that the same may conform to the record of the case in the Patent Office.

Signed and sealed this 27th day of March, A. D. 1951.

[SEAL]

THOMAS F. MURPHY,
Assistant Commissioner of Patents.
